(57) **CLAIM**

The ornamental design for an analytical device, as shown and described.

DESCRIPTION

FIG. 1 is a perspective view of an analytical device of our new design.

FIG. 2 is a front view of the analytical device of FIG. 1.

FIG. 3 is a back view of the analytical device of FIG. 1.

FIG. 4 is a side view of the analytical device of FIG. 1.

FIG. 5 is another side view of the analytical device of FIG. 1.

FIG. 6 is a top view of the analytical device of FIG. 1; and, FIG. 7 is a bottom view of the analytical device of FIG. 1. The broken lines illustrate portions of the analytical device that form no part of the claimed design.
